His Attorney.

UNITED STATES PATENT OFFICE.

FRIEDRICH GEHRTS, OF KARLSHORST, NEAR BERLIN, GERMANY, ASSIGNOR TO GENERAL ELECTRIC COMPANY, A CORPORATION OF NEW YORK.

AMPLIFIER CONNECTION.

Application filed September 10, 1923, Serial No. 661,739, and in Germany November 7, 1922.

In the connection of line conductors in duplex telephone connections with intermediate amplifiers the impedance of the two lines connected by the intermediate amplifiers or the impedance of each one of the lines and the artificial reproduction of the same must be carefully equalized in their dependency on the frequency. If this is not the case, back coupling takes place, so that a disturbing whistling of the amplifier is heard, whenever a certain degree of amplification is exceeded.

It is not possible in practice to obtain the equalization between the impedance of a line conductor and its artificial reproduction for all frequencies. As shown by theory and practice, the difficulties of the reproduction are especially great in the neighborhood of the natural frequency of the line conductor even with a careful reproduction of the impedance, as given by the method of calculation by R. S. Hoyt in the U. S. Patent No. 1,167,693 and by K. Kopfmüller in German Patent 380,964. The maintenance of equality between the line conductor and its reproduction is poor and the danger of whistling accordingly great.

My present invention consists in reducing the difficulties of equalization to a minimum, in that in the elements of the amplifier connection are inserted connecting means, for example, condensers, self-inductances and resistances, which are automatically variable according to the direction of speaking, so that the development of a disturbing auto-excitation, especially also within the range of the frequencies in the neighborhood of the natural frequency of the line conductor, is avoided. The means for obtaining such an action can be, for example, a choke coil, the inductance of which can generally be kept small by pre-magnetization, which latter is then compensated by a counter-magnetization, which becomes effective at the moment talking is started in the other direction. The counter-magnetization can also be obtained by means of a direction amplifier or similar rectifying arrangements.

The mode of operation of the connection is as follows:—

By means of the auxiliary magnetization the choke coil is premagnetized to beyond its saturation point and its impedance is relatively small. At the moment, however, when

the premagnetization is compensated by the countermagnetizing current, the inductance of the coils increases and therewith their impedance in accordance with the frequency range to be choked. The back coupling of the amplifier and whistling or the generation of oscillations are correspondingly reduced in the critical frequency range when the impedance is increased.

An example of one way of carrying out my invention is shown in the drawing. I have indicated a duplex connection in which there is arranged for each line an artificial line K_1 and K_2 . For each talking direction there is provided an amplifying tube R_1 and R_2 , and there is also in each line a direction amplifier R_{11} and R_{21} , which rectify a part of the talking currents after having been amplified. In order to obtain a favorable current curve for the compensation magnetization current two direction amplifiers can be employed instead of one.

The choke coil D_{r1} which lies in conductor $F_1 R_1 F_2$ is premagnetized by the winding S_1 . The talking currents arriving over the incoming line F_1 pass through the device R_1 , windings W_1 and X_1 of the coil D_{r1} and thence to the line F_2 . They also pass through the device R_{11} and are then conducted after being amplified to the winding T , of the choke coil D_{r1} , in such manner that there is produced in this winding a counter-magnetization compensating the premagnetization. At the same time the amplifier R_1 transmits the amplified talking currents over the windings W_1 and X_1 of the choke coil to the outgoing line F_2 . These talking currents now produce at the same time, in conjunction with the magnetization compensating current, a change in the choking limits of the coil for the critical frequency range. Disturbing frequencies can furthermore be eliminated in the known manner by parallel connected capacities C and by choke coils D connected up to the anode circuit of the direction amplifier.

The direction amplifier R_{21} and the choke coil D_{r2} operate in the same manner for the current coming from the line F_2 . Talking currents which arrive over the line F_2 pass through the amplifier R_2 , windings W_2 and X_2 of the coil D_{r2} and thence to the line F_1 . They also pass to the device R_{21} where they are caused to produce a magnetization of the

winding T_2 , which is counter to the pre-magnetization resulting from energization of the winding S_2 .

What I claim as new and desire to secure by Letters Patent of the United States is:—

5 1. The combination in a duplex telephone amplifier system of an impedance comprising a winding connected in each current path and means independent of said winding responsive to talking currents transmitted over the path in which said impedance is connected for automatically increasing the value of said impedance.

15 2. The combination in a duplex telephone amplifier system of an inductance comprising a winding connected in each current path and means independent of said winding responsive to talking currents transmitted over the path in which said inductance is connected for automatically increasing the value of said inductance.

25 3. The combination in a duplex telephone amplifier system of an impedance in each current path and means including a thermionic device for automatically varying the value of each impedance in accordance with the talking direction and thereby preventing the generation of oscillations.

30 4. The combination in a duplex telephone amplifier system of an inductance in each current path and means including a thermionic device for automatically varying the value of each inductance in accordance with the talking direction and thereby preventing the generation of oscillations.

35 5. The combination in a duplex telephone amplifier system of an iron core and a winding connected in each current path, means for producing a steady magnetization of each core, and means including an additional winding controlled by talking currents for producing a variable magnetization of each core in the opposite direction to the constant magnetization.

45 6. The combination in a duplex telephone amplifier system of an iron core and a winding connected in each current path, means for producing a steady magnetization of each core, and means including an additional winding for automatically decreasing the magnetization of each core whenever talking currents are transmitted over the path in which the first mentioned winding is connected.

55 7. The combination in a duplex telephone amplifier system of an iron core and a wind-

ing connected in each current path, means for producing a steady magnetization of each core, and means including an additional winding controlled by talking currents for automatically decreasing the magnetization of each core whenever talking currents are transmitted over the path in which the first mentioned winding is connected.

60 8. The combination in a duplex telephone amplifier system of an incoming line and an outgoing line, means for amplifying a portion of the currents received over the incoming line and delivering amplified currents to the outgoing line, an impedance connected to the outgoing line and means controlled by another portion of the currents received over the incoming line for varying the value of the impedance in the outgoing line.

65 9. The combination in a duplex telephone amplifier system of an incoming line and an outgoing line, means for amplifying a portion of the currents received over the incoming line and delivering amplified currents to the outgoing line, an inductance connected to the outgoing line and means controlled by another portion of the currents received over the incoming line for varying the value of the inductance in the outgoing line.

70 10. The combination in a duplex telephone amplifier system of an incoming line and an outgoing line, means for amplifying a portion of the currents received over the incoming line and delivering amplified currents to the outgoing line, an iron core inductance connected in the outgoing line, means for producing a steady magnetization of the core of said inductance, and means controlled by another portion of the received currents for varying the magnetization of said core.

75 11. The combination of a duplex telephone amplifier system of an incoming line and an outgoing line, means for amplifying one portion of the currents received over the incoming line and delivering amplified currents to the outgoing line, an iron core inductance connected in the outgoing line having a magnetizing winding to which a steady current is supplied and a magnetizing winding to which another portion of the received currents are supplied, and means for amplifying and rectifying said latter portion of the received currents.

In witness whereof, I have hereunto set my hand this 17th day of August, 1923.

FRIEDRICH GEHRTS.
